UNITED STATES PATENT OFFICE.

MADISON COOPER, OF MINNEAPOLIS, MINNESOTA.

COLD-STORAGE APPARATUS.

SPECIFICATION forming part of Letters Patent No. 659,468, dated October 9, 1900.

Original application filed July 3, 1899, Serial No. 722,633. Divided and this application filed March 5, 1900. Serial No. 7,338.
(No model.)

To all whom it may concern:

Be it known that I, MADISON COOPER, of Minneapolis, Hennepin county, Minnesota, have invented certain new and useful Improvements in Cold-Storage Apparatus, of which the following is a specification.

This invention relates to improvements in air-cooling apparatus designed especially for cold-storage houses, and particularly to an air-circulating system forming part of said apparatus; and the object of the invention is to provide means for securing a uniform distribution and circulation of the air throughout the storage-room.

15 The present application is filed as a division of my application, Serial No. 722,633, filed July 3, 1899.

The invention consists generally in an air-circulating system comprising means for forcing the cool air into the cold-storage rooms through suitable ducts arranged on the lower parts of the walls of the room, removing the warm air from the tops of said rooms through perforated ceilings and returning said air to the air-cooling room, from which after being cooled and preferably dried and purified it is again forced through the storage-room, and this circulation continues as long as desired.

20 The invention consists, further, in the construction and combinations hereinafter described, and particularly pointed out in the claims.

In the accompanying drawings, forming part of this specification, Figure 1 is a longitudinal vertical section of a refrigerating apparatus embodying my invention, showing in dotted lines the arrangement of the air-circulating ducts on the walls of the rooms, the air-cooling room, and the means for forcing the cold air into the rooms and drawing the warm air therefrom and through the air-cooling room. Fig. 2 is a horizontal section taken above the perforated ceilings of the rooms and showing the arrangement of the ducts for drawing the warm air from the rooms, this section being taken on line $y-y$ of Fig. 3. Fig. 3 is a transverse section through two rooms forming part of the cold-storage apparatus embodying my invention. Fig. 4 is a vertical section on line $x-x$ of Fig. 3.

25 In the drawings, 2 represents a suitable

structure or building or portion thereof forming part or the whole of a cold-storage plant and within which the refrigerating apparatus is arranged. The building may be of any suitable size, shape, or structure, provided with any desired number of rooms, and constructed of any suitable material.

30 The air-circulating system herein described may be applied to any number of rooms, although in the accompanying drawings I have for illustration shown its application to two rooms only. Arranged at any convenient point is the air-cooling room 3, within which is a series of pipes 5, through which any suitable refrigerant is circulated. I preferably provide in connection with these pipes a series of gutters 25 for holding a deliquescent salt. These gutters are described and claimed and their object is pointed out in my said 35 application, Serial No. 722,633, and the process of keeping the refrigerating-pipes clear of frost by means of a deliquescent salt is described and claimed by me in Letters Patent No. 644,847, issued March 6, 1900. The refrigerating-pipes may be arranged in any suitable manner in the air-cooling room and any suitable means may be used for circulating the refrigerating liquid through said pipes. I prefer to use for circulating the re- 40 frigerating liquid through the pipes to the air-cooling room the means shown and described in Letters Patent No. 629,341, issued to me July 25, 1899. An air-duct 7 is connected to the air-cooling room and to a suitable fan-casing 9, within which may be located a fan of any suitable construction. The position of the fan is indicated by the dotted circle in Fig.

45 1. An air-duct 11 leads from the fan-casing 9 and extends to the several rooms 44, which it is desired to maintain at a uniform temperature for cold-storage purposes. Suitable branch or distributing ducts 13 lead off from the main duct 11, and these ducts extend to points near the floors of the rooms to be cooled. Upon the walls of the storage-rooms I provide the transverse ducts 17, with which the ducts 13 connect. The ducts 17 are perforated through their top, bottom, and side walls, so as to distribute the air as uniformly as possible throughout the lower parts of the rooms. I also provide each room with a perforated

ceiling 19, extending across the top of the room and arranged a short distance below the usual ceiling of the room, so that the space above the perforated ceiling through which the warm air at the top of the room is uniformly collected or taken out. A return-duct 21 is connected to the space above each of the perforated ceilings, (see Figs. 2 and 3,) and a portion of the perforated ceiling nearest the duct is preferably placed on an incline, as shown in Fig. 4, so as to permit the ready passage of the air into the return-ducts 21. The return-ducts 21 connect, as shown in Figs. 1 and 2, with the air-cooling room 3. By the means described the air is caused to pass from the air-cooling room through the duct 11 and the branch ducts 13 into the lateral or transverse ducts 17, by which means it is evenly distributed through the lower parts of the rooms. Suitable slides or gates 18 may be provided at the points where the ducts 13 connect with the ducts 17, by means of which the passage of air into the ducts 17 or any of them may be regulated or cut off. The air passing into the room or rooms through the ducts 17 is distributed evenly in the lower part of the room and rises and passes through the perforations in the perforated ceilings. These ceilings form means of exit for the air at the tops of the rooms, and as the tendency of the air is to pass vertically as it becomes warm it follows that the cold air being distributed through the lower parts of the rooms and the warmer air being evenly drawn off at the tops of the rooms a uniform temperature throughout these rooms will be maintained.

The forced-air-circulating system herein described secures a practically-uniform temperature through the storage-rooms, and when used in connection with my process and means for purifying and drying the air hereinbefore referred to it secures purity of air and a proper degree of dryness or humidity thereof. The air in passing through the rooms is forced to cover with practical uniformity the entire cross-sectional area of each room. This is owing mainly to the use of the false ceiling at the top of each room and the side air-ducts by means of which air is supplied to the lower parts of the room. The side ducts are not obstructed by articles piled up on the floor of the room, nor can dirt which accumulates on the floor get into these ducts. The air from the side ducts passes laterally through and around the articles placed in the storage-room and then passes upward and through the perforated ceilings. The perforations in the side ducts are comparatively-small holes placed quite near together, obviating all strong drafts and at the same time insuring a very penetrating circulation, which will not allow of any dead corners. It is preferable to make the perforations twice as numerous on the bottom of the air-ducts 17 as on the top and to make only comparatively few such perforations in the front or face of the duct. This

insures the greatest supply of cold air along the floor of the room, and thus compels the cold air to come in contact with any articles on the floor of the room, and as the air rises with all of the articles above the floor. It is also preferable to make the holes in the false ceiling more numerous near the center of the room at a point farthest from the cold-air ducts and more widely separated as they approach the sides of the room directly over the cold-air duct 17. With this system of forced circulation a vigorous circulation of the air may be obtained and the moisture and impurities which are given off by the articles in the storage-room are quickly removed. They are not allowed to remain in the vicinity of the stored articles to work mischief, but are promptly hurried off to the air-cooling room, where they are for the most part absorbed or rendered harmless. It is also with this system and the means described in my pending application and the process described in my patent of March 6, 1900, as easy to control the humidity of the air as it is to control the temperature and with no bad effect on the other conditions in the storage-room.

As the details of the construction of the apparatus herein described may be considerably modified or changed without departing from my invention, I do not confine myself to such details as are herein shown and described.

Having thus described my invention, I claim as new and desire to secure by Letters Patent—

1. In a cold-storage apparatus, the combination, with a room provided with a perforated false ceiling, and with perforated transverse ducts on the lower part only of its walls, of means for forcing cold air into the room through said ducts and thereby distributing the cold air through the lower part of the room, and means for conducting the air off at the top of the room through said perforated ceiling, substantially as described.

2. The combination, in a cold-storage apparatus, with means for cooling the air, of a storage-room provided with transverse perforated ducts arranged upon the lower part only of its walls, a perforated false ceiling forming an air-duct at the top of the room, and means for conducting air to said transverse ducts and from said perforated ceiling, for the purpose set forth.

3. The combination, in an air cooling and circulating system, with means for cooling the air, of storage-rooms provided with transverse ducts on the lower parts only of their side walls, and with perforated false ceilings, ducts leading from the air-cooling room to said transverse ducts, return-ducts leading from the space above said ceiling to said air-cooling room, and means for drawing the air from said air-cooling room and forcing it through said cold-storage rooms, for the purpose set forth.

4. In a cold-storage apparatus, the combination, with a series of storage-rooms, of an air-cooling room, distributing-ducts leading from said air-cooling room to said storage-room, perforated transverse ducts arranged upon the lower parts only of the walls of the rooms and connected with the distributing-ducts, perforated ceilings arranged over the storage-rooms, and return-ducts leading from the spaces above said ceilings to said air-cooling room, for the purpose set forth.

5. In a cold-storage apparatus, the combination, with a storage-room provided with a perforated false ceiling, of transverse ducts

on the lower part of the walls of said storage-room, said ducts being provided on the front and at the top and bottom thereof with suitable perforations, means for forcing cold air into said storage-room through said ducts, and means for conducting the air off at the top of the room through said perforated ceiling, substantially as described.

In testimony whereof I have hereunto set my hand this 23d day of February, 1900.

MADISON COOPER.

In presence of—

A. C. PAUL,
M. C. NOONAN.
